(57) CLAIM

The ornamental design for a whistle with finger grip, as shown and described.

DESCRIPTION

FIG. 1 is a right side top perspective view of a whistle with finger grip.

FIG. 2 is right side bottom perspective view of the whistle with finger grip shown in FIG. 1.

FIG. 3 is a right side plan view of the whistle with finger grip shown in FIG. 1.

FIG. 4 is a left side plan view of the whistle with finger grip shown in FIG. 1.

FIG. 5 is a top plan view of the whistle with finger grip shown in FIG. 1.

FIG. 6 is a front plan view of the whistle with finger grip shown in FIG. 1.

FIG. 7 is a bottom plan view of the whistle with finger grip shown in FIG. 1; and,

FIG. 8 is a rear plan view of the whistle with finger grip shown in FIG. 1.

The left side is a mirror image of the right side.
